(57) **CLAIM**

The ornamental design for a floating drive-on boat dock extension, as shown and described.

DESCRIPTION

FIG. 1 is a perspective view of an extension attachable to a boat dock;

FIG. 2 is a top plan view of the extension;

FIG. 3 is a bottom plan view of the extension;

FIG. 4 is a front elevational view of the extension;

FIG. 5 is a rear elevational view of the extension; and,

FIG. 6 is a side elevational view of the extension, the right and left sides being mirror images of each other.
